UNITED STATES PATENT OFFICE.

JOHN KUSTER, JR., OF STAMFORD, CONNECTICUT.

MEANS FOR ATTACHING LOCKS.

SPECIFICATION forming part of Letters Patent No. 296,292, dated April 1, 1884.

Application filed February 19, 1883. (Model.)

To all whom it may concern:

Be it known that I, JOHN KUSTER, Jr., of Stamford, county of Fairfield, State of Connecticut, have invented a new and useful Improvement in Locks; and I do hereby declare the following to be a full, clear, and exact description of the same, reference being had to the accompanying sheet of drawings, forming part of this specification.

10 This invention relates to an improvement in locks; and the invention consists in a lock designed to be fitted within a circular opening in a door, constructed with turning wings or lugs to enter into the walls of the circular opening within which the lock is fitted, whereby the lock is fixed within said opening.

In the accompanying sheet of drawings, Figure 1 is a section showing the lock-case fixed to the end of a door. Fig. 2 is a plan or top view of same, partly in section. Fig. 3 is a detail of screw with lugs fixed to the heads thereof.

Similar letters of reference indicate like parts in the several figures.

25 This invention relates to an improvement in that class of locks in which the lock proper and the latch of the lock are separate devices fitted to opposite sides of a door connected by an intermediate plate or strip of metal and screws. This character of lock is usually contained within a circular opening, which is bored through the door to which the lock is to be attached, and it has been customary heretofore, after the lock proper has been placed in 30 a circular opening made for it, to apply the latch that is to be operated by the lock on the side of the door which is opposite to the lock, and to secure the lock and the latch mechanism by long screws passing through the outer 35 plate of the latch, through the circular hole of the door, and into some part of the case of the lock that is within the circular opening before mentioned; but since doors are of varying widths it has been necessary for the carpenter who attaches these locks to cut the screws designed to unite the lock with the latch, so as to render them of proper length for that purpose. This cutting of the screws, besides being attended with loss of time, is a 40 matter of some difficulty with carpenters, who as a rule are not supplied with proper tools for this purpose, and, besides, with such con-

struction the removal of the latch from the door for the purpose of repairing it or otherwise necessarily requires the removal of the 55 lock also, since to remove the latch these long connecting-screws referred to must be withdrawn.

To obviate this difficulty and enable locks of the character described to be easily and 60 promptly fixed in place, I construct my lock with two screws, A, which enter into the projections or parts a of the lock. The heads b of these screws are provided on one side with lugs or wings B, these lugs or wings having 65 one of their sides or edges, c, beveled and sharpened.

Now, when my lock, constructed substantially as described, is inserted within the circular opening C of the door and held in the 70 required position by one hand, a screw-driver inserted in the opening C through the back of the door is used to turn the screws A until the lugs or wings B are forced to cut their way into the adjacent and surrounding walls of the 75 opening C, which operation at once holds the lock within this opening and prevents it from being forced out of the same, the lugs not only acting as stops in so preventing it, but also acting as stops to prevent the lock from turning 80 within the circular opening C, and out of the position in which it is fixed. As these screws A are turned and the lugs or wings B are forced into the surrounding wood, the heads of the screws are by this operation turned 85 down and jam and bear tightly against the surface of the metal through which the screws are inserted, by this means effectually preventing the screws from accidentally turning within the circular opening C and the loosening of 90 the lock within the same. The latch mechanism of the lock may be now secured to the side of a door opposite the lock proper by the ordinary screws entering into the wood-work 95 of the door, and this latch mechanism can be removed for repairs without disturbing the lock proper, if desired; but when it is desired to remove the lock, it is simply necessary by means of a screw-driver to turn the screws A in a reverse direction, which will withdraw the 100 lugs or wings B from their engagement within the circular opening, and the lock can be pushed from its seat.

From the foregoing description it will be

seen no long and especially-constructed screws are required to unite the latch with the lock; no necessity exists for adapting the length of the screws to the width of the door to which the lock is to be applied, and no particularly careful adjustment is called for to secure the lock in place; but, to the contrary, any carpenter with little or no previous instruction can readily apply the locks of the kind described with even less trouble than he can apply locks and latches of ordinary construction.

I am aware that an anchor for locks provided with a slotted head having an angular spur or foot projecting from its base is not, broadly, of my invention.

Having now described my invention, what I

claim as new, and desire to secure by Letters Patent, is—

The lock-case provided at or near its inner end with the external lateral projections, *a*, ²⁰ having screw-threaded holes therein, combined with the screws *A*, positively engaging the screw-threaded holes in said lugs, and having slotted heads *b*, and the sharpened wings or lugs *B*, made directly on said head to enter the ²⁵ wood of the door to hold the lock in place, as shown and described.
